UNITED STATES PATENT OFFICE.

WILLIAM H. BURSTALL AND WALTER ADAMSON, OF OXNARD, CALIFORNIA.

SUCKER-ROD ELEVATOR.

1,341,166.

Specification of Letters Patent. Patented May 25, 1920.

Application filed June 28, 1919. Serial No. 307,318.

To all whom it may concern:

Be it known that we, WILLIAM H. BURSTALL and WALTER ADAMSON, citizens of the United States, residing at Oxnard, in the county of Ventura, State of California, have invented a new and useful Sucker-Rod Elevator, of which the following is a specification.

This invention relates to means for raising and lowering sucker rods into and out of artesian and oil wells.

An object of this invention is to provide an elevator which can be easily and quickly attached to and detached from the sucker rod to be raised or lowered.

Another object of our invention is to provide a semi-automatic latching means for sucker rods, which latching means will endure excessive strain and which will not loosen or release the sucker rod when the elevator is in operation.

A further object of this invention is to provide a sucker rod elevator of this character which will be adapted for attaching or detaching the same to or from a moving rod.

A further object of this invention is to provide a sucker rod elevator of the character referred to which will be simple and rapid in operation and strong and durable in construction.

Other objects and advantages will appear from the detailed subjoined description, it being understood that while we will herein after set forth a preferred form of our invention the same is not limited to such preferred form but contemplates changes in the details of construction, proportion and size thereof.

The accompanying drawings illustrate the invention.

Figure 1 is a perspective view of an elevator built in accordance with the provisions of this invention illustrating the elevator as applied to a sucker rod.

Fig. 2 is a front elevation of the same with the bail broken away.

Fig. 3 is a top plan view of the same with the bail broken away.

Fig. 4 is a vertical section taken on the line indicated by x^4-x^4 in Fig. 3.

Fig. 5 is a view similar to that in Fig. 3, except that the cover plate is removed, illustrating the latch in locked position.

Fig. 6 is a view similar to Fig. 5 except that the latch is in open position.

Fig. 7 is a top plan view of the elevator body with the latch mechanism and slide removed.

Fig. 8 is a vertical section taken on the line indicated by x^8-x^8 in Fig. 6.

Fig. 9 is a vertical section taken on the line indicated by x^9-x^9 in Fig. 3.

Fig. 10 is a perspective view of the slide for our elevator.

Fig. 11 is a perspective view of one of the latch members of our elevator.

The elevator comprises a body 1 which is provided at opposite edges with gudgeons 2, which form pivots engaging the bearings 3 of a bail 4. The body 1 is formed with a rod receiving way or slot 5, which way extends from the center of the body 1 and has parallel side walls 6 terminating in outwardly diverging portions 7. The inner end of the way 5 is preferably curved in a semi-circular manner, as at 8, to form a bearing for a sucker rod.

The upper portion of the body 1 is cut away, as illustrated in Fig. 7, to provide a latch mechanism receiving recess 9. The recess 9 is formed with parallel side walls 10 which extend to the periphery at the rear of the body 1 and which communicate at their forward ends with outwardly diverging portions 11, the latter forming seats for a purpose hereinafter referred to. The boundary of the recess 9 is completed by the walls 12 which extend from the seats 11 to the apex of the walls 6 and 7 of the slot 5.

A rib 13 is formed at the rear of the body 1 intermediate the sides 10 of the recess 9 and is reduced as at 14 adjacent the said sides 10, which reduced portions 14 form rectangular guideways for a purpose hereinafter referred to.

A pair of jaws 15 is provided with overlapping and overlapping ears 16 which are pivoted by a pivot rod 17 mounted within a bore 18 formed within the body 1, which bore is situated intermediate the rib 13 and the inner end of the slot 5. Each of the jaws 15 is formed in its inner edge with a semicircular recess 19, which recesses adjoin to form a circular bearing for a sucker rod, when the jaws are in latched position as illustrated in Fig. 3.

The jaws 15 are provided with flat outer edges 20, which edges 20 are in parallel relation with the sides 10 of the recess 9 when the jaws are in latched position as illustrated in Fig. 5.

The forward ends of the jaws 15 are provided with shoulders 21 between which and the seats 11 are positioned coil springs 22. The springs 22 tend to maintain the jaws 15 in the latched position illustrated in Fig. 5. The shoulders 21 are so formed that when the jaws 15 are in the latched position illustrated in Fig. 5 the inner faces 23 of the shoulders 21 coincide with the sides 6 of the way 5.

The inner edges of the jaws 15 diverge outwardly at 24 so that contact of the said diverging faces 24 with a sucker rod will force the jaws 15 apart to receive the rod. 15 Lugs 25 are positioned adjacent the edges 6 of the slot 5 and adapted to limit the movement of the jaws 15 by engaging with the said jaws at the end of recesses 26 formed therein.

20 The parallel rods 27 of a U-shaped slide 28 are slidably received within the rectangular guideways 14 and are adapted to engage the side walls 10 of the recess 9 and the flat outer edges 20 of the jaws 15 to lock the jaws 25 in latched position as illustrated in Fig. 5. The transverse portion 29 of the slide 28 forms a grip for manipulating the slide. The ends of the rods 27 are provided with lugs 30 which are adapted to engage the reduced portions of the rib 13 to limit the outward movement of the slide 28. The inward movement of the slide 28 is limited by abutments 31 which are adapted to engage the outer edge of the reduced portions of the rib 13. The 35 slide 28 is secured against the initial outward movement when in the latched position illustrated in Fig. 5 by means of depressions 32 formed in the rods 27 adjacent the abutments 31, which depressions receive 40 balls 33 carried by coil springs 34, the latter being mounted within recesses 35 formed in the rectangular guideways 14.

The latch mechanism above described is held within the recess 9 by means of a cover 45 36. The cover 36 has the same general outline as the top of the body 1 and is formed with a rod receiving way 37 corresponding with the rod receiving way 5 and is preferably formed at its end with a circular 50 curve 38 of larger diameter than the circle formed by the recesses 19 of the jaws 15 when the jaws are in latched position. As a protection to the slide 28 the body 1 and the cover 36 may be provided with guards 39. 55 The preferred form of our invention illustrated in the drawings is adapted to be readily assembled as follows:

60 The pivot rod 17 is inserted through the ears 16 of the jaws 15 and the jaws mounted within the body 1 by forcing the pivot rod 17 into the bore 18. The coil springs 22 are inserted between the shoulders 21 of the jaws 15 and the seats 11 of the recess 9. The coil springs 34 are mounted within

the recesses 35 formed in the rectangular 65 guideways 14 and the balls 33 mounted thereon. The slide 28 is then positioned with its parallel rods 27 mounted within the rectangular guideways 14. The cover 36 is then mounted on the body 1 by suitable 70 securing means 40. It is to be noted that the latching mechanism of the preferred form of our invention requires no bolt, screw or other securing means in assembly other than the cover retaining means referred to. 75

In operation our invention provides a distinct advance over the prior art in its simplicity and rapidity of operation. Our elevator is applied to the casing rod by withdrawing the slide 28 and forcing the sucker 80 rod against the jaws 15 as illustrated in Fig. 6. The contact of the rod and jaws 15 will then spread the jaws apart. Similarly with the slide 28 in open position a pull by the operator upon the grip portion 29 will cause 85 a sucker rod secured within the elevator to force open the jaws 15 to disconnect the elevator from the rod.

In practice, therefore, the operator need only manipulate the grip portion 29 to draw 90 the slide 28 to open position, after which the elevator becomes automatic in that the sucker rod may be inserted between or withdrawn from the jaws 15 by merely forcing a contact between the jaws and the sucker 95 rod.

The necessary manipulation of the slide 28 may be performed by the operator with one hand, thus allowing the elevator to be attached or released with great rapidity and 100 ease.

The elevator may thus be applied to either a stationary or moving rod and can likewise be released from such.

Furthermore the relation of parts is such 105 that our elevator is extremely durable in construction and constitutes a maximum safeguard against accidental loosening of the grip upon a suspended sucker rod.

We claim:

1. A sucker rod elevator comprising a bail, a body connected to said bail having a radially extending rod receiving way, shiftable latch means to secure a rod within said way, and a slide to secure said latch means 115 in latched position.

2. A sucker rod elevator comprising a bail, a body connected to said bail having a radially extending rod receiving way, shiftable latch means to secure a rod within said 120 way, said latch means being adapted to be opened by the pressure of a rod when the elevator is applied to or removed from the same, and a shiftable member to lock said latch means in latched position.

3. A sucker rod elevator comprising a bail, a body connected to said bail having a radially extending rod receiving way, latch 125

- means adapted to secure a rod within said way, and a wedge member adapted to lock said latch means in latched position. 1. In a sucker rod elevator the combination of a body having a radially extending rod receiving way, shiftable jaws and a wedge member adapted to lock said jaws in latched position to secure a rod within the elevator. 5. In a sucker rod elevator the combination of jaws adapted to be opened by a rod, and a wedge member adapted to lock said jaws in latched position to secure a rod within the elevator. 10. In a sucker rod elevator the combination of a bail, a body connected to said bail and provided with a rodway, jaws pivoted to said body, and a wedge adapted to lock said jaws in latched position to secure a rod within said way. 15. In a sucker rod elevator the combination of a bail, a body connected to said bail having a rod receiving recess, means to secure a rod within said way, said means being adapted to be opened by the pressure of the rod when the elevator is applied to or removed from a rod, and means to secure said last named means in locking position. 20. In a sucker rod elevator the combination of movable jaws adapted to lock a rod within said elevator, said jaws being adapted to be opened by the pressure of the rod when the elevator is applied to or removed from a rod, and means to secure said jaws in closed position. 25. In a sucker rod elevator the combination of a body having a rod receiving way, shiftable latch means to secure a rod within said way, and shiftable means to secure said latch means in latched position. 30. In a sucker rod elevator the combination of a bail, a body connected to said bail and having a radially extending rod receiving way, movable jaws mounted in said body, and a wedge member to secure said jaws in closed position to prevent the passage of a rod through said way. 35. In a sucker rod elevator the combination of a bail, a body connected to said bail, said body having a rod receiving way and a latch receiving recess, jaws pivoted within said recess, and a slide member adapted to secure said jaws in closed position. 40. In a sucker rod elevator the combination of a bail, a body connected to said bail having a rod receiving way, movable jaws adapted to secure a rod within said way, and a wedge member adapted to lock said jaws in closed position. 45. In a sucker rod elevator the combination of a bail, a body connected to said bail having a rod receiving way, pivoted jaws adapted to secure a rod within said way and a U-shaped slide adapted to lock said jaws in closed position. 50. In a sucker rod elevator the combination of a bail, a body connected to said bail having a rod receiving way, pivoted jaws adapted to secure a rod within said way, and a U-shaped slide adapted to engage said jaws to lock the same in closed position. 55. In a sucker rod elevator, the combination of a bail, a body connected to said bail, said body having a rod way and a latch mechanism receiving recess, movable jaws adapted to secure a rod within said way, coil springs inserted between said jaws and the walls of said recess to yieldably hold said jaws in closed position, and a slide member engaging said jaws to hold said jaws in closed position. 60. In a sucker rod elevator the combination of a bail, a body connected to said bail having a radially extending rod receiving way, and jaws having semicircular meeting faces adapted to adjoin to form a circular closure for a rod in said way. 65. In a sucker rod elevator the combination of a bail, a body connected to said bail having a rod receiving way, movable jaws having semicircular meeting faces adapted to adjoin to form a circular closure for a rod in said way, means to releasably hold said jaws in closed position, and means to lock said jaws in closed position. 70. In a sucker rod elevator the combination of a bail, a body connected to said bail having a rod receiving way, movable jaws having semicircular meeting faces adapted to adjoin to form a circular closure for a rod in said way, means to releasably hold said jaws in closed position, and means to lock said jaws in closed position. 75. In a sucker rod elevator the combination of a bail, a body connected to said bail having a rod receiving way, movable jaws having semicircular meeting faces adapted to adjoin to form a circular closure for a rod in said way, means to releasably hold said jaws in closed position, and means to lock said jaws in closed position. 80. In a sucker rod elevator the combination of a bail, a body connected to said bail having a rod receiving way, movable jaws having semicircular meeting faces adapted to adjoin to form a circular closure for a rod in said way, means to releasably hold said jaws in closed position, and means to lock said jaws in closed position. 85. In a sucker rod elevator the combination of a bail, a body connected to said bail having a rod receiving way, movable jaws having outwardly diverging faces for engagement with a rod to open said jaws, and shiftable means to secure said jaws in closed position. 90. In a sucker rod elevator the combination of a bail, a body connected to said bail having a rod receiving way, a recess formed on one face of said body with side walls, movable jaws pivoted within said recess adapted to prevent the passage of a rod through said way, and a slide adapted to wedge between said jaws and said side walls to secure said jaws in locked position. 100. In testimony whereof we have hereunto set our hands at Oxnard, California, this 20th day of June, 1919.

WILLIAM H. BURSTALL.
